UNITED STATES PATENT OFFICE.

ALLAN S. HUTCHINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LET-OFF.

Application filed June 8, 1928. Serial No. 283,971.

This invention relates to let-offs for looms and it is the general object of the invention to provide a weighted let-off operating to utilize the weight of the warp beam to tension the warp threads.

One of the best ways to secure even tension on warp threads so as to insure uniform cloth is to subject the warp threads to the pressure of a weight which is moved as the warp thread is used up. This method is found to be very satisfactory in the weaving of such fabrics as hat bands where uniformity of cloth is absolutely essential. It is an important object of my present invention to employ the general principle of a weight by supporting the warp beam partly by the warp threads and partly on a pair of endless chains, feeding the chains so as to lower the warp beam periodically as the same reaches a predetermined elevation. In this way the warp threads will be constantly subjected to the weight of the beam to insure uniformity of tension.

During weaving the weight of the warp beam decreases and in order to compensate for this I contemplate the use of a counter-weight which may be varied, the tension on the warp being substantially the difference between the weight of the beam and the pressure exerted by the counterweight, the latter being lessened as weaving continues so that the difference between these two pressures will remain constant to insure uniform tension in the warp thread.

It is a further object of my present invention to provide means for manually lowering the warp beam at the time of a pick-out.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a side elevation of a loom made according to my present invention with the warp beam in down position,

Fig. 2 is a rear elevation taken in the direction of arrow 2, Fig. 1, and

Figs. 3 and 4 are operating views showing the control shield in shielding and non-shielding positions, respectively.

Referring particularly to Figs. 1 and 2, I

have shown the loom frame 10 having take-up mechanism 11 to receive cloth C. The warp threads W extend from the cloth rearwardly through harness mechanism not shown and may extend over a guide roll 12. From the roll the warp extends to a beam 13 having a shaft 14. Located at each side of the loom is a bracket 15 which has an upwardly opening vertically extending slot 16 through which the corresponding end of the shaft 14 extends. Each bracket 15 is provided with a support 17 which is secured to the bracket for vertical adjustment by means of a foot 18. Each foot has a vertical slot 19 through which pass bolts 20 by means of which the support 17 may be held in adjusted vertical position.

Each bracket 15 has an upwardly projecting rear horn 21 and a second or forward horn 22. Extending between the horns 22 is a shaft 23 to each end of which is secured a sprocket 24 so that said sprockets and shaft turn together. Each horn 21 is provided with a stud 25 on which is freely rotatable a sprocket 26 substantially in alignment with the corresponding sprocket 24.

The lower end of each bracket 15 is provided with an upwardly extending but downwardly opening slot 27 through which extends a rod 28 to each end of which is secured a sprocket 29. A sprocket 30 is secured to each end of the warp beam shaft 14 and all of the sprockets on one side of the loom will be substantially in the same vertical plane. At each side of the loom is a chain which meshes with the sprockets at that side of the loom, as shown in Fig. 1. Weights 31 may be hung on the rod 28 and manipulated in a manner to be described hereinafter.

A horizontal cross shaft 32 is rotatable through bearings 33 and 34 carried by the upper part of one of the brackets 15, that located at the right of Fig. 2 as shown herein. To the rear end of said shaft is a worm 35 which meshes with worm gear 36 secured to the shaft 23. Said worm, worm gear and sprockets 24 together with shaft 23, therefore, are seen to move together.

A hand wheel 36 at the front end of the shaft 32 may be provided if desired. The worm and worm gear provide means for rotating the sprockets 24 and in order to

complish this result under power I provide a constant rotating shaft 37 to which is secured a cam 38 which acts on a cam lever 39 movable about a fixed pivot 40. Said lever 39 has pivoted thereto as at 41 a feed pawl 42 which as shown in Figs. 3 and 4 is urged toward a ratchet wheel 43 by a small compression spring 44. The ratchet wheel is fast with respect to the shaft 32 and when rotated will cause movement of the worm 35. The worm 35 is long enough to engage bearing 34 under normal conditions so that said bearing prevents movement of the worm to the right as viewed in Fig. 1 to prevent rotation of the sprocket and shaft 23.

The feeding of the ratchet is under control of the warp beam, the control being effected by means of a shield 45 mounted on the upper end of a vertically adjustable rod 46. Said rod is operatively connected to a control lever 47 pivoted as at 48 to a portion of the support 17 to be movable vertically with the latter. The rearwardly extending arm 49 of the lever 47 extends over the shaft 14 as set forth in Figs. 1 and 2.

If desired, the weight of the empty beam may be regulated to give the desired tension on the warp threads and weights 31 may be added to the rod 28 to an extent sufficient to counterbalance the weight of the yarn on the warp beam. Under these conditions and with the warp beam in a relatively low position, the shield 45 will be raised to the position shown in Fig. 3 so that the worm 35 will act to hold the sprockets 24 in fixed position. The vertical portion or limb 50 of the chain E will therefore be held against downward movement and as the warp is used up in making cloth the warp beam 13 will turn around its axis in a clockwise direction, causing the sprocket 30 to climb up said portion 50 by slow degrees. As the warp beam reaches a predetermined elevation the shaft 14 thereof will engage the lever 47 and cause the latter to rock in a clockwise direction about the stud 48. This will result in the lowering of the shield 45 to the position shown in Fig. 4 where it will be seen that the pawl 42 is in position to engage the teeth of the ratchet 43.

As the cam 38 lifts the lever 39 the ratchet will be rotated in a counter-clockwise direction as viewed in Fig. 2 and the worm 35 will be given such a movement as will turn the sprocket 24 in a counter-clockwise direction as viewed in Fig. 1 to lower the limb or portion 50 of the chain E. This downward movement of portion 50 is accompanied by a corresponding descent of the beam and attendant raising of the shaft 28 and the weights carried thereby. The arm 49 is weighted to follow the shaft 14 and the shield 45 will be moved upwardly to assume the position shown in Fig. 3 to

prevent further positive feeding of the chain.

The operation just described is repeated throughout the running of the loom, the warp beam moving up gradually and being fed back positively, the warp being subjected to the tension due only to the lifting of the beam. Because of the fact that the chains are continuous the operation as described will continue irrespective of the length of the warp wound on the beam relatively to the length of the chain.

As previously stated the tension on the warp depends upon the difference between the weight of the beam and the counterweights 31 and in order to keep this difference constant I arrange to remove certain of the weights 31 from time to time as the diameter of the warp beam decreases.

At the time of pickout it is necessary to let the fell of the cloth back and this may be accomplished by rotation of the hand wheel 36. If the warp beam be in a relatively high position at the time a pickout is made the beam will fall of its own weight to take up cloth which is let back by loosening the takeup 11. If it should so happen, however, that the shaft 14 were resting on the support 17 so that further downward motion of the beam to take up slack is impossible the hand wheel 36 may be rotated in such a way as to lift the section 50 of the chain, causing rotation of the beam in a direction to take up the slack warp. This will be possible because of the fact that under these conditions the shield 45 will be up due to the lowered position of the beam and the pawl will not act to prevent retrograde movement of the ratchet 43.

From the foregoing it will be seen that I have provided a simple let-off wherein the tension on the warp threads is due solely to a weight which is raised as the warp is consumed, the weight being periodically lowered. It will further be seen that by the use of the endless chain I am able to combine with the weight of the beam an element having a variable weight so that the net weight which is brought to bear upon the warp threads may be kept constant as the diameter of the beam decreases. It will further be seen that the worm and worm gear operate to hold one of the sprockets and therefore one point of the chain relatively fixed to afford a point for which the system may be controlled. It will also be seen that the feeding is conditional upon the requirements of the loom and is automatic in its control. Furthermore, when it is necessary to make a pickout the chain may be moved in a reverse direction if necessary to place the warp beam in the proper position, the location of the shield permitting such reverse motion of the parts.

Having thus described my invention it

will be seen that changes and modifications may be made therein by those skilled in the art without departing from the spirit and scope of the invention and I do not wish to be limited to the details herein disclosed, but what I claim is:

1. In a let-off for looms, a warp beam, means to guide the warp beam in a vertical direction, an endless chain on which the beam is supported and up which the beam climbs as warp is used, and means depending upon the position of the beam to feed the chain and lower the beam.
2. In a let-off for looms, a warp beam, means to guide the warp beam for vertical movement, a sprocket secured to and turning with the beam, a chain meshing with the sprocket, means to hold a portion of said chain stationary under normal conditions, the sprocket and beam being raised along the chain as the beam rotates due to the using up of the warp, and means dependent upon the position of the beam to feed said chain in a direction to lower the beam when the latter reaches a predetermined elevation.
3. In a let-off for looms, a warp beam mounted for motion in a direction to have a vertical component, a sprocket movable about a fixed axis, an endless chain meshing with the sprocket, a second sprocket secured to and rotating with the beam and meshing with the chain, means to hold the first sprocket normally stationary to prevent movement of the chain so as to cause the beam to move upwardly along the chain as the beam rotates incident to paying off warp during the weaving operation, and means controlled by the position of the warp beam to rotate the first named sprocket to give the chain a feeding movement in a direction to lower the beam.
4. In a let-off for looms, a warp beam guided for movement in a direction having a vertical component, a sprocket rotatable about a fixed axis, a second sprocket secured to and rotatable with the beam, a chain connecting and meshing with said sprockets, means associated with the first named sprocket to hold the chain stationary under normal conditions, rotary movement of the beam incident to paying off warp during the weaving operation causing the second named sprocket to move upwardly along the chain to raise the beam, a regularly moving feeding device, and means controlled by the vertical position of the beam to connect said feeding device to the first named sprocket when the beam reaches a predetermined elevation to turn said sprocket and move the chain in a direction to lower the beam.
5. In a let-off for a loom, a beam guided for movement in a direction to have a vertical component, said beam being supported

by and tensioning the warp threads, means to cause said beam to be elevated through the rotary motion of the beam incident to the paying off of warp from the beam, and means acting on the beam to lower the latter when the beam has attained a predetermined elevation.

6. In a let-off for a loom, a warp beam guided for motion in a direction having a vertical component, an endless chain, a sprocket movable about a fixed axis meshing with the chain, a second sprocket secured to and rotating with the beam and meshing with the chain, means to prevent rotation of the first sprocket under normal conditions so that as the beam rotates due to paying off warp the second sprocket and beam will climb upwardly along the chain and variable means to weight the chain.

7. In a let-off for a loom, a warp beam guided for motion in a direction having a vertical component, an endless chain, a sprocket movable about a fixed axis meshing with the chain, a second sprocket secured to and rotating with the beam and meshing with the chain, means to prevent rotation of the first sprocket under normal conditions so that as the beam rotates due to paying off warp the second sprocket and beam will climb upwardly along the chain and variable means to set the chain, and means to feed the chain in a direction to effect lowering of the beam after the latter has attained a predetermined elevation.

8. In a let-off for looms, a warp beam guided for movement in a direction having a vertical component, a sprocket rotatable about a fixed axis, a second sprocket moving with and secured to the beam, a third guide sprocket, an endless chain extending over the first and third sprockets and under the second sprocket, and means operatively connected to the lower part of the chain to weight the latter, the second sprocket and beam climbing up a portion of the chain due to the rotary movement of the beam incident to paying off warp, means acting on the beam to lower the latter when the beam has attained a predetermined elevation, and means acting normally to prevent downward movement of that portion of the chain up which the second sprocket moves.

9. In a let-off for looms, a warp beam guided for movement in a direction having a vertical component, a sprocket rotatable about a fixed axis, a second sprocket moving with and secured to the beam, a third guide sprocket, an endless chain extending over the first and third sprockets and under the second sprocket, and means operatively connected to the chain to weight the latter, the second sprocket and beam climbing up a portion of the chain due to the rotary movement of the beam incident to paying off warp, means acting on the beam to lower the

latter when the beam has attained a predetermined elevation and means acting normally to prevent downward movement of that portion of the chain which the second 5 sprocket moves, said weighted means being variable to be reduced as the weight of the beam decreases.

10. In a let-off for looms, a warp beam guided for movement in a direction having a vertical component, a sprocket rotatable about a fixed axis, a second sprocket moving with and secured to the beam, a third guide sprocket, an endless chain extending over the first and third sprockets and under the 15 second sprocket, and means operatively connected to the lower part of the chain to weight the latter, the second sprocket and beam climbing up a portion of the chain due to the rotary movement of the beam incident 20 to the paying off of warp, and means acting normally to prevent downward movement of that portion of the chain which the second sprocket moves, and means to rotate the first sprocket in a direction to effect 25 lowering of the beam when the latter reaches a predetermined elevation.

11. In a let-off for looms, a warp beam movable in a direction having a vertical component, a sprocket movable about a fixed 30 axis, a worm gear secured to and moving with the sprocket, a worm meshing with the worm gear, a second sprocket secured to and rotating with the beam, a chain meshing with the sprockets, the worm cooperating 35 with the worm gear to prevent rotary movement of the first named sprocket under normal conditions so that as the warp beam rotates the second sprocket will climb up the chain due to the rotary movement of the beam incident to the paying off of the warp to raise the beam, and means operative to 40 rotate the worm when the beam reaches a predetermined elevation to cause feeding of the chain in a direction to effect downward movement of the beam.

12. In a let-off for looms, a warp beam movable in a direction having a vertical component, a sprocket movable about a fixed axis, a worm gear secured to and moving 50 with the sprocket, a worm meshing with the worm gear, a second sprocket secured to and rotating with the beam, a chain meshing with the sprockets, the worm cooperating 55 with the worm gear to prevent rotary movement of the first named sprocket under normal conditions so that as the warp beam rotates the second sprocket will climb up the chain due to the rotary movement of the beam incident to the paying off of the warp to raise the beam, and means operative to 60 rotate the worm when the beam reaches a predetermined elevation to cause feeding of the chain in a direction to effect downward movement of the beam, said means including a pawl and ratchet dependent for their

operation on the position of the beam and operatively connected to the worm.

13. In a let-off for looms, a warp beam movable in a direction having a vertical component, a sprocket movable about a fixed axis, a worm gear secured to and moving with the sprocket, a worm meshing with the worm gear, a second sprocket secured to and rotating with the beam, a chain meshing with the sprockets, the worm cooperating 70 with the worm gear to prevent rotary movement of the first named sprocket under normal conditions so that as the warp beam rotates the second sprocket will climb up the chain due to the rotary movement of the beam incident to the paying off of the warp to raise the beam, and means operative to 75 rotate the worm when the beam reaches a predetermined elevation to cause feeding of the chain in a direction to effect downward movement of the beam, a feed pawl, a ratchet therefor rotatable with and rigid with respect to the worm, and a shield operatively positioned by the beam relatively to the feed pawl and movable to effect co-operation 80 between the ratchet and pawl when the beam reaches the said predetermined position.

14. In a let-off for a loom, a warp beam movable in a direction having a vertical component, a sprocket movable about a fixed axis, a worm gear secured to and moving with the sprocket, a worm meshing with the worm gear, a second sprocket secured to and rotating with the beam, a chain meshing 95 with the sprockets, the worm cooperating with the worm gear to prevent rotary movement of the first named sprocket under normal conditions so that as the warp beam rotates the second sprocket will climb up the chain due to the rotary movement of the beam incident to the paying off of the warp to raise the beam, and means operative to 100 rotate the worm when the beam reaches a predetermined elevation to cause feeding of the chain in a direction to effect downward movement of the beam, and manual means to rotate the worm.

15. In a let-off for looms, a warp beam movable in a direction having a vertical component, a sprocket movable about a fixed axis, a worm gear secured to and moving with the sprocket, a worm meshing with the worm gear, a second sprocket secured to and rotating with the beam, a chain meshing 115 with the sprockets, the worm cooperating with the worm gear to prevent rotary movement of the first named sprocket under normal conditions so that as the warp beam rotates the second sprocket will climb up the chain due to the rotary movement of the beam incident to the paying off of the warp to raise the beam, and means operative to 120 rotate the worm when the beam reaches a predetermined elevation to cause feeding of the chain in a direction to effect downward movement of the beam, and manual means to rotate the worm.

- chain in a direction to effect downward movement of the beam, said means including a feed pawl, a ratchet therefor rotatable with and rigid with respect to the worm, 5 and a shield operatively positioned by the beam relatively to the feed pawl and movable to effect cooperation between the ratchet and pawl when the beam reaches the said predetermined position, and manual means 10 to rotate the worm, said beam when in a position lower than the predetermined elevation moving the shield to prevent engagement of the pawl and ratchet whereby said manual means is independent of the ratchet 15 when the warp beam is in lower position.
16. In a let-off for looms, a warp beam movable in a direction having a vertical component, a rotary member secured to and

moving with the beam, a second rotary member movable about a fixed axis, mechanism to gear said rotary means together, means to hold the second rotary member normally stationary to hold the mechanism relatively fixed, the first rotary member climbing up the mechanism due to the rotary movement of the beam incident to the paying off of the warp from the beam during the weaving operation, and means to effect rotation of the second rotary member when the beam reaches a predetermined vertical position to effect lowering of the beam through said mechanism.

In testimony whereof I have hereunto affixed my signature.

ALLAN S. HUTCHINS.
